CATHODE RAY TUBE SCREEN

Martin Ploke, Dresden, Germany, assignor to
 Zeiss Ikon Aktiengesellschaft, Dresden, Germany

Application January 21, 1938, Serial No. 186,239
 In Germany January 18, 1937

13 Claims. (Cl. 250—164)

The invention relates to improvements in a method of light control in cathode ray tubes, particularly for television purposes.

It has been proposed heretofore in the television art to employ light control methods which are based upon the thermic effect of the electron bombardment and in which for instance, a metallic plate arranged in a highly evacuated space was heated to incandescence according to the brightness of the individual picture points. Practical tests, however, disclosed that a considerable dissipation of the irradiated plate occurs, resulting in a very short life of the cathode ray tube. It is also difficult in these known arrangements to produce a sufficient large irradiation capacity to heat the plate to incandescence.

The principal object of the present invention is a method of light control for television purposes in which the change in shape of conductive or insulating material, when subjected to heat, is made use of.

In accordance with the invention, a screen composed for instance of a number of reeds, is arranged transversely in the path of the electron beam. The reeds are of such a structure that they change their shape in response to the heating effect of the electron beam and thereby cause a locally different shading of the beam of light striking the screen. The light passing through the screen is projected onto a picture screen.

It is also an object of the invention to employ for the production of the aforesaid reeds a so-called bi-metal composed of two different strips of sheet metal welded or soldered together and having each a different coefficient of thermal expansion.

Other objects of the invention will appear from the following description of the invention with reference to the accompanying drawings, in which

Fig. 1 illustrates diagrammatically a Braun tube constructed in accordance with the present invention.

Figs. 2 and 3 illustrate in elevation and end view respectively one element of the screen within the Braun tube.

Figs. 4 and 5 illustrate diagrammatically the effect of an electron beam upon two differently constructed screens,

Fig. 6 illustrates diagrammatically a modified embodiment of a Braun tube, and

Figs. 7 and 8 illustrate in front elevation and side view the screen employed in the Braun tube of Fig. 6.

Referring to Fig. 1 the Braun tube 1 is pro-

vided with a neck 2 in which are arranged the customary means for producing, concentrating and deflecting an electron beam. These means comprise in the illustrated embodiment an indirectly heated cathode 11, a control electrode 12, an anode 13, the lens electrodes 14 and 15 and the two pairs of deflecting plates 16 and 17 respectively. The potentials required for the various electrodes are taken from the potentiometer 18.

In the envelope proper of the Braun tube is mounted a screen 3. The same consists in accordance with the present invention of a plurality of parallel strips 4 mounted on parallel threaded rods 5. The strips 4 are spaced from each other a predetermined distance by suitable spacers. The Figs. 2 and 3 illustrate one of the strips 4 of the screen 3 in elevation and end view respectively. It will be noted that each strip 4 is provided with a number of transverse slots in one longitudinal edge thereof to produce so a comb-like structure having teeth 6, each having its free ends curved toward the adjacent lower strip.

The lens 1 arranged in front of a source of light 9 projects a beam of substantially parallel light rays onto the screen 3. The light rays passing through said screen are projected by a lens 8 onto a picture screen 10, which receives an image of the screen 3. The screen 3 is electrically connected with the anode and with respect to the latter is positively charged. The reeds 6 are curved in such manner that when the electron current is zero no light can pass through the screen. When an electron beam strikes the screen, however, the curvature of the reeds corresponding to the individual picture points is nullified and according to the modulation of the electron beam the screen 3 is rendered locally permeable to light. The time period during which the reeds retain their changed shape is governed by the heat conductivity of the reeds.

If the length of the reeds is for instance .2 inch and their thickness is .002 inch, a heating of the reeds of 212° F. is sufficient to cause a noticeable change in shape of the bimetallic reeds. The distance of the parallel strips 4 from each other is preferably made equal or approximately equal the width of the reeds, in order to produce substantial symmetric picture points. The total sum of the reeds of the screen 3 should be equal or larger than the number of the picture points of the television picture. Therefore, the intended controlling effect will be obtained with the method of the present invention at con-

siderable lower temperatures and accordingly with less irradiation energy as in the methods heretofore practiced. Since the method of the invention requires a lower irradiation energy the 5 cathode ray tube can be operated with lower potentials, which is another advantage over other thermic methods of the prior art.

Fig. 4 illustrates diagrammatically a point-like illumination of the picture screen arranged 10 rectly behind the reed screen. The electron beam, when striking a normally curved reed 6, causes the latter to straighten out and the light can now pass at this point through the reed screen.

Fig. 5 illustrates diagrammatically a point-like shading of the picture screen. In this modified arrangement the reeds are normally straight and the light passes normally through all the slots in the reed screen. An electron beam striking a 20 reed will cause the latter to assume a curved shape, thus causing a point-like shade on the picture screen. In this manner the dark values of the television picture are controlled. It is hereby necessary to select the modulation potential of the electron beam so that the maximum electron current appears at the dark spots of the television picture.

According to the invention the metallic reeds may also be blackened and be arranged in front 30 of a white surface so that the electron beam during scanning produces differently dense shadow on the white surface. In this manner it is possible to observe the television picture in daylight. In the latter case the light reflected from 35 the screen may be employed for the projection of the picture.

As indicated in the Figs. 4 and 5 the reeds 6 may be supported by the picture screen or may be fused into a glass plate. A white picture 40 screen is then applied to the glass plate.

The Figs. 6, 7 and 8 illustrate a modified arrangement of the invention. While the means for producing, concentrating and deflecting the electron beam are the same as in Fig. 1 and 45 therefore designated with similar reference characters, the reed screen 3^a is of different construction. It consists of a glass plate 21 provided with a smaller number of reeds 6, preferably of just a sufficient number necessary for one line 50 of the picture. These reeds are repeatedly swept over by the electron beam. The light passing thereby through this single line is projected by the lens 8 onto a rotating mirror 19 or a mirror wheel, which in turn reflects the light onto the 55 picture screen 20 upon which the picture is assembled line by line. This arrangement has the advantage that the construction of the reed screen is much simpler, since only reeds for one line are necessary. The mirror wheel 19 has to 60 be arranged in such a manner and has to be rotated with such a speed that each mirror of the mirror wheel assembles one picture.

In this embodiment of the invention also a substantial gain in brightness is obtained compared 65 with those television methods which are based upon the deflection and control of a single light point.

According to the Figs. 7 and 8, the reeds 6 are fused into the glass plate 21. The rear ends of 70 the reeds which project from the rear face of the glass plate 21 are provided with conductive strips 22 to conduct the heat away from the reeds.

It is also contemplated to provide other means 75 for conducting the heat away from the reeds.

Preferably the time constant of the fading away of the change in shape is selected so that within the period of a picture change the deformation of the reeds returns to zero. It is also possible to cool the supporting structure of the reed screen and if desired the supporting means structure may be extended through the wall of the tube envelope and thus increase the dissipation of the heat. The screen supporting structure may be fused to the wall of the envelope which latter 10 then may be cooled by water.

It is believed obvious that the invention is not limited to the embodiments illustrated and described hereabove, but that other forms may be adopted within the scope of the appended claims. 11

What I claim is:

1. In a cathode ray tube of the type containing means for producing a cathode ray beam, particularly for television, a screen upon which said beam is focused, said screen being capable of transmitting light under cathode ray bombardment in amounts proportional to the intensity of the ray, said screen comprising a plurality of bimetallic reeds mounted in a single plane and extending each substantially at a right angle to said plane, said reeds being deformed momentarily when being struck by the cathode ray beam.

2. In a cathode ray tube of the type containing means for producing a cathode ray beam, particularly for television, a screen upon which said beam is focused, said screen being capable of transmitting light under cathode ray bombardment in amounts proportional to the intensity of the ray, said screen composed of a plurality of spaced parallel bimetallic strips having one of 25 their longitudinal edges slotted to form a comb-like structure, said strips being mounted in a single plane so that the teeth of the comb-like structures extend substantially at right angles to said plane, the teeth of said comb-like structures being 30 adapted to be deformed momentarily by the heat of the cathode ray beam striking the said teeth.

3. In a cathode ray tube of the type containing means for producing a cathode ray beam, particularly for television, a screen upon which 45 said beam is focused, said screen being capable of transmitting light under cathode ray bombardment in amounts proportional to the intensity of the ray, said screen comprising a plurality of bimetallic reeds mounted in a single plane and extending each substantially at a right angle to 50 said plane, said reeds being deformed momentarily when being struck by the cathode ray beam, the total numbers of said reeds in said screen being at least as large as the number of picture points 55 in one line of the picture to be reproduced.

4. In a cathode ray tube of the type containing means for producing a cathode ray beam, particularly for television, a screen upon which said beam is focused, said screen being capable of 60 transmitting light under cathode ray bombardment in amounts proportional to the intensity of the ray, said screen comprised of a plurality of spaced parallel bimetallic strips having one of their longitudinal edges slotted to form a comb-like structure, said strips being mounted in a single plane so that the teeth of the comb-like structures extend substantially at right angles to said plane, the teeth of said comb-like structures being adapted to be deformed momentarily 65 by the heat of the cathode ray beam striking the said teeth, the total numbers of teeth in said screen being at least as large as the number of picture points in the picture to be reproduced.

5. In a cathode ray tube of the type containing 75

means for producing a cathode ray beam, particularly for television, a screen upon which said beam is focused, said screen being capable of transmitting light under cathode ray bombardment in amounts proportional to the intensity of the ray, said screen composed of a plurality of spaced parallel bimetallic strips having one of their longitudinal edges slotted to form a comb-like structure, said strips being mounted in a single plane so that the teeth of the comb-like structures extend substantially at right angles to said plane, the distance between each two parallel bimetallic strips being substantially as great as the width of one tooth, the teeth of said comb-like structures being adapted to be deformed momentarily by the heat of the cathode ray beam striking the said teeth.

6. In a cathode ray tube of the type containing means for producing a cathode ray beam, particularly for television, a screen upon which said beam is focused, said screen being capable of transmitting light under cathode ray bombardment in amounts proportional to the intensity of the ray, said screen composed of a plurality of spaced parallel bimetallic strips having one of their longitudinal edges slotted to form a comb-like structure, said strips being mounted in a single plane so that the teeth of the comb-like structures extend substantially at right angles to said plane, the distance between each two parallel bimetallic strips being substantially as great as the width of one tooth, the total numbers of teeth in said screen being at least as large as the number of picture points of the picture to be reproduced, the teeth of said comb-like structures being adapted to be deformed momentarily by the heat of the cathode ray beam striking the said teeth.

7. In a cathode ray tube of the type containing means for producing a cathode ray beam, particularly for television, a screen upon which said beam is focused, said screen being capable of transmitting light under cathode ray bombardment in amounts proportional to the intensity of the ray, said screen comprising a white picture screen and in front thereof a plurality of bimetallic reeds extending substantially at right angles to said picture screen, said reeds being blackened and being adapted to be deformed momentarily by the heat of the cathode ray striking the said reeds, thereby causing locally different shadings of a beam of light projected onto the front face of said picture screen.

8. In a cathode ray tube of the type containing means for producing a cathode ray beam, particularly for television, a screen upon which said beam is focused, said screen being capable of transmitting light under cathode ray bombardment in amounts proportional to the intensity of the ray, said screen comprising means forming a white picture screen, and a plurality of bimetallic reeds attached to said picture screen means and extending at right angles thereto, said reed being blackened and being adapted to be deformed momentarily by the heat of the cathode ray beam striking said reeds, thereby causing locally different illumination of the said picture screen by a beam of light projected through said plurality of reeds onto the said white picture screen.

9. In a cathode ray tube of the type containing means for producing a cathode ray beam, particularly for television, a screen upon which said beam is focused, said screen being capable of transmitting light under cathode ray bombard-

ment in amounts proportional to the intensity of the ray, said screen comprising means forming a white picture screen, and a plurality of bimetallic reeds attached to said picture screen means and extending at right angles thereto, said reeds being blackened and normally being straight and when struck by the cathode ray beam assume momentarily a curved shape at their outer free ends, due to the heat of the cathode ray beam, thereby causing locally different illumination of the said picture screen by a beam of light projected through said plurality of reeds onto the said white picture screen.

10. In a cathode ray tube of the type containing means for producing a cathode ray beam, particularly for television, a screen upon which said beam is focused, said screen being capable of transmitting light under cathode ray bombardment in amounts proportional to the intensity of the ray, said screen comprising means forming a white picture screen, and a plurality of bimetallic reeds attached to said picture screen means and extending at right angles thereto, said reeds being blackened and normally being curved at their free outer ends and when struck by the cathode ray beam are straightened out momentarily, owing to the heat of the cathode ray beam, thereby causing locally different illumination of the said picture screen by a beam of light projected through said plurality of reeds onto the said white picture screen.

11. In a cathode ray tube of the type containing means for producing a cathode ray beam, particularly for television, a screen upon which said beam is focused, said screen being capable of transmitting light under cathode ray bombardment in amounts proportional to the intensity of the ray, said screen comprising a glass plate and a plurality of bimetallic reeds fused into said glass plate so as to project therefrom at right angles, said reeds being adapted to be deformed momentarily by the heat of the cathode ray beam striking said reeds.

12. In a cathode ray tube of the type containing means for producing a cathode ray beam, particularly for television, a screen upon which said beam is focused, said screen being capable of transmitting light under cathode ray bombardment in amounts proportional to the intensity of the ray, said screen comprising a glass plate and a plurality of bimetallic reeds fused into said glass plate so as to project therefrom at right angles, the total numbers of reeds mounted in said glass plate being at least as large as the number of picture points in one line of the picture to be reproduced, said reeds being adapted to be deformed momentarily by the heat of the cathode ray beam striking said reeds.

13. In a cathode ray tube of the type containing means for producing a cathode ray beam, particularly for television, a screen upon which said beam is focused, said screen being capable of transmitting light under cathode ray bombardment in amounts proportional to the intensity of the ray, said screen comprising a glass plate, a plurality of bimetallic reeds fused into said glass plate so as to project therefrom at right angles with both of their ends, the forwardly projecting ends of said reeds being adapted to be deformed momentarily by the heat of the cathode ray beam striking said forwardly extending ends of the reeds, and means attached to the rearwardly projecting ends of said reeds for facilitating the dispersion of heat from said reeds.
